UNITED STATES PATENT OFFICE.

ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WARP STOP MOTION.

Application filed June 28, 1923. Serial No. 648,373.

This invention relates to improvements in a warp stop motion of the general type shown in my prior Patent No. 1,360,638, issued November 30, 1920.

- 5 It is the object of my present invention to improve the construction therein shown in certain important respects, whereby the utility and convenient operation of the stop motion is substantially increased.
- 10 With this general object in view, one feature of my invention relates to the provision of improved devices for retaining the vibrator bars and the supporting bushings therefor in the end frame of the stop motion.
- 15 Another feature of my invention relates to the provision of novel and conveniently accessible means for adjusting the contact member by which the latch is moved out of

20 the path of the actuating arm.

Further features of my invention relate to arrangements and combinations of parts which will be hereinafter described and more particularly pointed out in the appended claims.

25 A preferred form of my invention is shown in the drawings in which—

Fig. 1 is a side elevation of a loom having my improved stop motion applied thereto;

30 Fig. 2 is a plan view of the stop motion;

Fig. 3 is an end elevation of the stop motion, taken along the line 3—3 in Fig. 2;

Fig. 4 is a rear view of the parts shown in Fig. 3;

35 Fig. 5 is a view similar to Fig. 3 but showing the parts in a different position;

Fig. 6 is a rear elevation of the opposite end of the stop motion;

Fig. 7 is a sectional end elevation, taken 40 along the line 7—7 in Figs. 2 and 6;

Fig. 8 is a plan view, taken along the line 8—8 in Fig. 3;

Fig. 9 is a detail front elevation, looking in the direction of the arrow 9 in Fig. 8;

45 Fig. 10 is a perspective view of a spacing bar support or bracket; and

Figs. 11 and 12 are detail sectional elevations, taken along the lines 11—11 and 12—12 of Fig. 7.

50 Referring particularly to Figs. 1 and 2, I have shown my improved stop motion as mounted upon a loom having loom sides 20 provided with brackets 21 in which posts 22 are vertically adjustable. Angle bars 23 are

adjustably secured in the posts 22 and portions of these angle bars 23 extend forward horizontally to provide supports upon which the end frames 24 and 25 of the stop motion are forwardly and rearwardly adjustable.

55 Vibrator bars 26 (Fig. 2) and spacing bars 27 (Fig. 7) extend across the loom between the frames 24 and 25, the spacing bars 27 separating the different banks of drop wires. One or more intermediate supports 28 (Fig. 2) are provided to support the 60 vibrator bars between their ends and to hold them in lateral alignment with the spacing bars and drop wires.

65 The spacing bars 27 are mounted on the end frames 24 and 25 by adjustable brackets or supports 30 (Fig. 10). These supports 30 are provided with hook-like projections 31 adapted to engage end lugs 32 on the frames 24 and 25 and to firmly support the 70 vibrator bars in position. The supports 30 are slotted at 33 to receive the spacing bars and are preferably provided with three contact points 34 which engage the end plates and provide a three-point bearing thereon. These supports 30 are made of sheet metal, 75 so that they may yield slightly without breakage when applied to an end frame having an irregular or uneven surface.

80 The intermediate supports and the separator bar supports are not claimed herein but 85 form the subject matter of co-pending applications of John Regan Serial No. 648,353, and of Ahlin and Pentecost Serial No. 648,340.

85 The actuating mechanism of my improved stop motion is in general similar to that shown and described in my prior patent and comprises an actuating arm or lever 40 (Fig. 3) pivoted on a stud 41 fixed on a projection of the end frame 24 and regularly oscillated by a link 42 from an actuating cam and cam lever shown in Fig. 1. The arm 40 has a depending projection 43 (Fig. 3) having a shoulder 44 positioned to engage a latch 45 when the latter is in raised position.

90 The latch 45 is pivoted on an arm 46 which in turn is mounted upon the stud 41 previously described. The latch 45 forms a portion of a three-armed lever or latch device having the additional arms 47 and 48. 95 The arm 47 has a projection 49 engaged by a contact member or plate 50. A screw 51 passes through the plate 50 and is threaded 100

in the arm 47 and an additional screw 52 is threaded in the arm 48 and the point thereof is received in a slight depression in the outer surface of the plate 50. The plate 50 is thus adjustably secured to the three-armed lever or latch device and may be adjusted therein about the projection 49 as a pivot by tightening or loosening the screws 51 and 52.

The plate 50 extends downward into the path of a stud 54 (Fig. 4) mounted on one of a series of swing arms 55 by which the vibrator bars 26 are oscillated. One of the arms 55 has an upwardly extending portion 56 to which is pivoted a U-shaped rod 57. The rod 57 passes through a rocking pin 58 in a projection 59 of the actuator arm 40. A collar 60 on the rod engages the stud 58 on one side and a spring on the rod 58 is interposed between a washer 62 engaging the stud 58 and a collar 63 adjustable on the rod 57.

The actuator arm 40 is thus yieldingly connected to oscillate the arms 55 and to cause the stud 54 to periodically engage the plate 50, swinging the latch 45 out of the path of the shoulder 44. The arm 46 which supports the latch is also connected by a rod or link 65 to a shipper lever 66 in such a manner that the shipper will be released when the rod 65 is moved toward the front of the loom or to the left in Fig. 1.

If one of the vibrator bars is held from angular movement by one of its drop wires, as fully described in my prior patent, the yielding oscillating movement of the arms 55 will be prevented and the stud 54 will not move a sufficient distance to remove the latch 45 from the path of the shoulder 44. Under these conditions, these parts will engage as shown in Fig. 5, swinging the arm 46 to the left to stop the loom. The parts may be very conveniently timed by adjustment of the contact plate 50 by means of the screws 51 and 52.

45 The vibrator bars 26 are preferably inserted in the stop motion through the end frame 25. For the purpose of supporting the bars 26 and conveniently securing them in position, I have provided the locking devices shown in Figs. 6, 7, 11 and 12. The vibrator bars are of non-circular cross section and the ends of the bars are preferably inserted in bushings 70 loosely receiving the bars 26 and rotatable in bearings in the end frame 25. The bushings 70 are provided with heads 71 limiting inward movement thereof.

50 A locking plate 72 is pivoted at 73 on the frame 25 and is provided with a series of openings 74 which are aligned with the bushings 70 and the vibrator bars 26 when the plate is in locking position. These openings 74 will permit the bars 26 to pass therethrough but will not afford passage for the heads 71 of the bushings 70.

55 A second locking plate 75 is also pivoted

to the frame 25 at 73 and lies closely adjacent the plate 72 on the outer side thereof. The plate 75 has no openings aligned with the bars 26 and thus prevents longitudinal movement thereof when in operative position. The plate 72 may be secured in position by a cotter pin 76 (Fig. 11) extending through an opening in the end of the plate but the plate 75 is provided with a notch or slot 77 (Fig. 7) passing freely over the cotter pin 76.

60 In assembling the parts, the bushings 70 may first be placed in position in the end frame 25, after which the locking plate 72 is swung downward and is secured by the cotter pin 76. The vibrator bars can then be inserted lengthwise through the bushings 70 and may be retained in position by the locking plate 75, being easily removed therefrom by swinging the plate upward when desired.

65 Having thus described my invention and the advantages thereof, I do not wish to be limited to the details herein disclosed otherwise than as set forth in the claims, but what I claim is:—

1. In a warp stop motion, an end frame, a plurality of vibrator bars of non-circular cross section, bushings for said bars rotatable in said frame, means to hold said bushings in said frame, and additional means to hold said bars in said bushing.

2. In a warp stop motion, an end frame, a plurality of vibrator bars of non-circular cross section, bushings for said bars rotatable in said frame, a locking plate for said bushings having openings for said bars, and a second locking plate for said bars.

3. In a warp stop motion, an end frame, a plurality of vibrator bars of non-circular cross section, bushings for said bars rotatable in said frame, a locking plate for said bushings having openings for said bars, and a second locking plate for said bars, said plates being pivoted to said frame and being separately movable to and from locking position.

4. In a warp stop motion, an end frame, a plurality of vibrator bars of non-circular cross section, bushings for said bars rotatable in said frame, a locking plate for said bushings having openings for said bars, and a second locking plate for said bars, said plates being mounted for separate movement on said frame and a fastening device being provided for said first plate only.

5. In a warp stop motion, a pivoted actuating arm, a pivoted release arm, a shipper release rod connected thereto, a latch device movable by engagement with said actuating arm to operate said release arm and rod, a contact member adjustably secured to said latch device, and means to engage and move said contact member and to thereby remove said latch from operative position during

the continued movement of said actuating member in one direction.

6. In a warp stop motion, a pivoted actuating arm, a pivoted release arm, a shipper release rod connected thereto, a latch device movable by engagement with said actuating arm to operate said release arm and rod, a flat contact plate having a supporting bearing on said latch device, a pair of adjusting

screws engaging said plate on opposite sides of said bearing to adjust said plate angularly on said bearing point as a pivot, and means to engage said contact plate and to move said latch device from operative position.

In testimony whereof I have hereunto affixed my signature.

ELBRIDGE R. HOLMES.
